(57) **CLAIM**

The ornamental design for an “ergonomic paint brush sleeve,” as shown and described.

DESCRIPTION

FIG. 1 is a perspective view showing our new design;

FIG. 2 is a front view thereof;

FIG. 3 is a side view thereof;

FIG. 4 is a bottom view thereof; and,

FIG. 5 is a top view thereof.

The broken lines showing a paint brush are including for the purpose illustrating environmental structure that forms no part of the claimed design.
